UNITED STATES PATENT OFFICE.

LOUIS SANDERS, OF NEW YORK, N. Y.

DESIGN FOR A BELT.

SPECIFICATION forming part of Design No. 83,895, dated January 8, 1901.

Application filed December 10, 1900. Serial No. 39,499. Term of patent 3½ years.

To all whom it may concern:

Be it known that I, LOUIS SANDERS, a citizen of the United States, and a resident of the city of New York, borough of Brooklyn, 5 in the county of Kings and State of New York, have invented and produced a new and original Design for a Belt, of which the following is a full, clear, and exact description, reference being had to the accompanying drawing, forming, a part thereof, which represents a plan view of a belt embodying the features of my design.

The leading feature of the design consists in the surface decoration of the belt, in which 15 two lines extend longitudinally of the belt one above the other, the lower line conforming to the contour of the lower longitudinal edge of the belt, while the upper line conforms to the lower line, except at the back 20 central portion of the belt, at which point the upper line is arched.

The minor features of the design consist in the point at the central portion of the lower longitudinal edge of the belt, in the upward direction of the arched portion of the upper 25 decorative line on the outer face of the belt, and the panel between the lower decorative line and the arched portion of the upper decorative line.

Having thus described my invention, I 30 claim as new and desire to secure by Letters Patent—

The design for a belt as herein shown and described.

In testimony whereof I have signed my 35 name to this specification in the presence of two subscribing witnesses.

LOUIS SANDERS.
